DISPENSING CONTAINER FOR POWDERED MATERIAL

Jerome Gould, Encino, Calif., assignor to United States Borax & Chemical Corporation, Los Angeles, Calif., a corporation of Nevada

Filed Mar. 23, 1964, Ser. No. 79,136

Term of patent 14 years

(Cl. D58—17)

FIG. 1 is a side elevational view of a dispensing container for powdered material, showing my new design;

FIG. 2 is an elevational view of the side opposite that shown in FIG. 1;

FIG. 3 is an end elevational view taken from the right of FIG. 1;

FIG. 4 is an end elevational view taken from the left of FIG. 1;

FIG. 5 is a top plan view thereof; and

FIG. 6 is a bottom plan view thereof.

I claim:

The ornamental design for a dispensing container for powdered material, as shown.
